FIG. 1

FIG. 2

FIG. 4

FIG. 3

FIG. 5

FIG. 1 is a view in perspective of a tire showing my new design, it being understood that the tread design shown in full lines is continued throughout the circumference of the tire;

FIG. 2 is an enlarged fragmentary plan view of the crown portion thereof;

FIG. 3 is an enlarged fragmentary view in elevation of one side thereof, the side opposite that shown being a mirror image;

FIG. 4 is a fragmentary sectional view thereof as seen from the line 4-4 of FIG. 2; and

FIG. 5 is a fragmentary transverse sectional view thereof as seen from the line 5-5 of FIG. 2.

I claim:

The ornamental design for a tire, substantially as shown and described.
